CLAIM

The ornamental design for an impeller, as shown and described.

DESCRIPTION

FIG. 1 is a first perspective view of an impeller, taken from above.

FIG. 2 is a second perspective view of the impeller, taken from below.

FIG. 3 is a front view of the impeller of FIG. 1.

FIG. 4 is a back view of the impeller of FIG. 1.

FIG. 5 is a left-side view of the impeller of FIG. 1.

FIG. 6 is a right-side view of the impeller of FIG. 1.

FIG. 7 is a top view of the impeller of FIG. 1.

FIG. 8 is a bottom view of the impeller of FIG. 1.

FIG. 9 is a cross-sectional view of the impeller taken along the line 9-9 shown in FIG. 7; and,

FIG. 10 is a cross-sectional view of the impeller taken along the line 10-10 shown in FIG. 7.

The broken lines represent features of the impeller which form no part of the claimed design.

1 Claim, 10 Drawing Sheets(56)
